UNITED STATES PATENT OFFICE

147,540

DESIGN FOR AN ADJUSTABLE HIGH CHAIR

Markus Engelberg and Goldie Engelberg,
Brooklyn, N. Y.

Application April 20, 1946, Serial No. 128,812

Term of patent 3½ years

(Cl. D15—1)

To all whom it may concern:

Be it known that we, Markus Engelberg and Goldie Engelberg, citizens of the United States and both residing at 1462 Union Street, county of Kings and State of New York, have invented a new, original, and ornamental Design for an Adjustable High Chair, of which the following is a specification, reference being had to the accompanying drawing, forming part thereof.

Figure 1 is a front view of our new design of adjustable high chair;

Figure 2 is a side view thereof, showing the back and foot rests in their upright positions; and

Figure 3 is a side view thereof showing the back and foot rests in inclined positions.

We claim:

The ornamental design for an adjustable high chair, substantially as shown.

MARKUS ENGELBERG.
GOLDIE ENGELBERG.
